DESIGN FOR AN ALPHABET FOR FORMING MONOGRAMS OR THE LIKE

Michael Chernow, Brooklyn, N. Y.

Application August 5, 1933. Serial No. 48,936

Term of patent 3½ years

To all whom it may concern:

Be it known that I, MICHAEL CHERNOW, a citizen of the United States, and residing at Brooklyn, in the county of Kings and State of New York, have invented a new, original, and ornamental Design for An Alphabet for Forming Monograms or the like, of which the following is a specification, reference being had to the accompanying drawing, forming part hereof, and in which

Fig. 1 is a plan view of an alphabet for form-

ing monograms or the like showing my design, the alphabet being devoid of the letters M, O, Q, U, V, X and Y.

Fig. 2 is a perspective view of one of the letters of such alphabet.

I claim:

The ornamental design for an alphabet for forming monograms or the like, substantially as shown and described.

MICHAEL CHERNOW.
